Edward L. Wood, Detroit, Mich., assignor, by direct and mesne assignments, to Gar Wood Industries, Inc., a corporation of Michigan

Application October 22, 1954, Serial No. 32,771

Term of patent 14 years

(Cl. D14—30)

Fig. 1

Fig. 2

Fig. 3

Fig. 1 is a side elevational view of a wheel trim embodying my new design;

Fig. 2 is a profile view showing generally the cross sectional contour of the wheel trim of Fig. 1; and

Fig. 3 is a fragmentary perspective view thereof.

The dot and dash line showing of a conventional wheel and tire assembly in Figs. 1 and 2 is for illustrative purposes only.

I claim:

The ornamental design for a wheel trim, substantially as shown and described.
